DESIGN FOR A COMBINED CHENILLE JACKET AND HOOD

Melvin D. Brod, New York, N. Y.

Application March 19, 1940, Serial No. 91,068

Term of patent 3½ years to all whom it may concern:

Be it known that I, Melvin D. Brod, a citizen of the United States and resident of New York city, the county of New York and State of New York, have invented a new, original, and ornamental Design for a Combined Chenille Jacket and Hood, of which the following is a specification, reference being had to the accompanying drawing, forming a part thereof:

Fig. 1 is a front elevational view of a combined chenille jacket and hood, showing my new design.

Fig. 2 is a rear elevational view of the same.

Fig. 3 is a side elevational view of the same.

I claim:

The ornamental design for a combined chenille jacket and hood, as shown.

MELVIN D. BROD.
